UNITED STATES PATENT OFFICE.

SIMON DENK, OF BROOKLYN, NEW YORK, ASSIGNOR TO ECONOMIC TWIST DRILL COMPANY, OF NEW YORK, N. Y., A CORPORATION OF NEW YORK.

ROLLS FOR SIMULTANEOUSLY REDUCING AND RELIEF-RIBBING TWIST-DRILLS.

1,151,247.

Specification of Letters Patent. Patented Aug. 24, 1915.

Application filed February 24, 1913. Serial No. 750,085.

To all whom it may concern:

Be it known that I, SIMON DENK, a citizen of the United States, residing in Brooklyn, in the county of Kings and State of New York, have invented certain new and useful Improvements in Rolls for Simultaneously Reducing and Relief-Ribbing Twist-Drills, of which the following is a specification.

This invention relates to rolls for twisting fluted rods, or blanks, to form twist-drills, and for simultaneously reducing the preliminarily-formed drill-blanks and rolling relief-ribs on the blanks during the twisting operation.

15 In the drawings forming part of this specification, Figure 1 is a plan view showing a drill feeding between the rolls, the lower roll being shown in full lines and the upper roll in dotted lines. Fig. 2 is a front view of the lower roll and of the drill being twisted and completed, as seen from below in Fig. 1. Fig. 3 is a fragmentary sectional view in line J¹-J¹, Fig. 1, showing the lower part of the upper roll 1, and showing 20 an oblique section of the drill fitting in the channels of the roll-face. Fig. 4 is a similar sectional view in line J-J, Fig. 1, of a portion of the lower roll 2, with the drill in place thereon. Fig. 5 is a front elevation, 25 on a reduced scale, of the pair of rolls.

Similar characters designate like parts in all the figures.

30 My present invention is in part in the nature of an improvement on the drill-twisting rolls described in Letters Patent of the United States, No. 761,880, granted to me June 7, 1904. In my present improved rolls, however, the shapes and relative positions of the several component faces of the drill-engaging surfaces are materially changed, as will be evident by a comparison of the drawings, especially of Figs. 3 and 4 of the present drawing with the corresponding views 35 given in my said prior patent. These changes involve a rotative change of position of the drill-blank relatively to the roll-axes, and a change of the roll-faces whereby to form the outer-surfaces of the drill-blank to a different shape, and the addition of 40 new features consisting of roll-grooves located in a particular manner whereby to reshape the blank and form thereon the narrow projecting ribs along the forward edges 45 of the "lands", as hereinafter more fully set forth.

The drill-blanks may, in practice, be preliminarily formed by forging with suitable straight grooves of flutes lengthwise of cylindrical rods and then twisted to approximate shape in such rolls as described in the aforesaid patent; these rolls being set at an angle to each other and adapted for giving a twist to the grooves, so as to produce a twist-drill. As in that former case, the present rolls are intended to work upon axes which are in parallel planes; but the axes are each located at an angle to the drill of about fifteen to twenty degrees and at an angle to each other or about thirty to forty degrees.

45 The upper and lower rolls 1 and 2 are mounted upon power-driven arbors or axles 3 and 4, respectively, these being preferably horizontal. The upper axle and roll may lie at an angle of about thirty degrees or more to the lower axle and roll, as will be understood from an examination of Fig. 1. The upper roll has a circumferential ridge 5 and the lower roll a ridge 6 for engaging within the opposite flutes 7 and 8 in the drill-blank, these ridges being suitably rounded or shaped in section so as to match or nearly match the grooves, and to hold the drill in the proper rotative position, as in Figs. 3 and 4.

50 The upper roll 1 is placed at such a point over the lower roll 2 that a vertical line intersecting the axes of both rolls passes through the centers or crowns of both ridges 5 and 6, as will be understood by reference to Figs. 1, 2 and 5. These ridges by reason of their crosswise arrangement become the principal factors in correctly twisting the drill-rod 9, which is drawn horizontally between the rolls at an angle about as illustrated in Fig. 1 and in the drawing of said prior patent. The movement of the drill may be effected by the grip of the rolls thereon, these being power-driven and rotating in unison.

55 Referring now to the lower roll 2, it will be seen that it is provided with a conical or flaring flange 10, which forms a shallow concave outward curve from the base 11 of one flank of the ridge 6, the purpose of this flange being to afford a support or guide for one side 12 of the drill-rod. Upon the opposite flank of the ridge 6 is formed a flaring flange 13, which may also be slightly concaved and may be more abrupt than the

flange 10 and preferably does not extend so deeply into the roll, the inner termination of said flange or its junction with the flank of the ridge being indicated at 14. In other words, the flank or side of the ridge 6 which joins the flange 13 is preferably not so deep as the side which joins the ridge 10, as clearly seen in Figs. 2 and 4. The flange 13 is also intended to assist in guiding the 10 drill. The upper roll is similar to the lower roll, being provided with a flange 15, corresponding to the lower flange 10, and also with a flange 16, corresponding to the lower flange 13; but it will be noted that the rolls 15 are placed reversely, so that the flange 16 overlies the flange 10 and the flange 15 overlies the flange 13, thereby producing like effects upon diametrically opposite sides of the drill-rod as it feeds between the rolls. 20 These features of the rolls operate in a general way after the manner set forth in my aforesaid patent, but with the changes already referred to.

As in said prior patent, each of the flanges 25 10 and 13 coöperates independently with the ridge 6 in guiding or controlling the drill, and the same is true of the flanges upon the upper roll, and while I prefer to use both flanges upon each roll, still my invention is 30 not limited to rolls each having two flanges, so long as a flange upon one roll supports the drill upon a side diametrically opposite to the side of the rod which is supported by a like flange upon the other roll—that is, so 35 long as the rolls have reverse arrangement.

The ridges 5 and 6 are suitably formed to nearly fit the original grooves 19, formed in the drill-blanks, and so as to accord with the final forming of the grooves desired. It 40 will be understood that the twisting of the drill is effected by the lateral pressure of the ridges within the grooves of the drill-blanks, and where the ridges alone are depended upon to effect the twisting this lateral pressure usually has the effect of mis- 45 shaping the drill; but by provision of the drill-supporting flanges 10, 13, 15, and 16 this difficulty is minimized or avoided.

Between the ridge 6 and the curved flange-face 10, of the lower roll 2, I make 50 a rib-forming channel 11, having, preferably, an abrupt shoulder on its outer side, as at 11^a. In the upper roll 1, a corresponding rib-forming channel is made at 31 between the ridge 5 and the flange surface 15, and said channel has a corresponding abrupt shoulder at 31^a, Fig. 3. Being thus formed,

when properly operated as set forth, the rolls are now adapted to substantially reduce the drill-blank by a re-rolling of the 60 same during and simultaneously with the final correction of the twist, and thus from an unribbed drill-blank to form the abruptly projecting relief-ribs 20 and 21 on the fully completed drill body, as 9. The ribs 20 65 and 21 may then be trued off on their outer surfaces, for straightening and reducing them to an accurate dimension, either before or after hardening the drill; and this operation may be repeated from time to time 70 as required, without thereby materially widening the bearing surface, which in practice is an important advantage in this special class of drills, which are intended mainly for very coarse work,—as in ship- 75 yards and in bridge and boiler work,—and to be used without any finishing subsequent to the rolling, except on the relief ribs as here stated.

Having thus described my invention, I 80 claim:—

1. In a machine for forming fluted twist-drills, a pair of rolls mounted at an angle to each other and each having a circumferential ridge for forming drill-flutes, said 85 ridge being flanked on each side with a concavo-cone-like drill supporting flange, one of said flanges being longer than the other and having its narrow end of less diameter than the narrow end of the other drill supporting 90 flange, and a concavo-cone-like rib-forming channel disposed at the narrow end of said longer flange adjacent to said ridge and thus remotely disposed from the enlarged ends of said drill supporting 95 flanges.

2. In a machine for forming fluted twist-drills, a pair of rolls mounted at an angle to each other and each having a circumferential ridge for forming drill-flutes, said 100 ridge being flanked on each side with a drill supporting flange, one of said flanges being longer than the other and having its narrow end of less diameter than the narrow end of the other drill supporting flange, and 105 a rib-forming channel disposed at the narrow end of said longer flange adjacent to said ridge and thus remotely disposed from the enlarged ends of said drill supporting flanges.

SIMON DENK.
